XYLOPHONE

Harry Zimmerman, New York, N. Y.

Application September 26, 1942, Serial No. 459,753

4 Claims. (Cl. 84—403)

This invention relates to xylophones and more particularly to the manner of mounting and maintaining the musical sounding members in place on the supporting frame at all times.

One object of the invention is the provision of a musical instrument of this nature in which the musical sounding members are supported and maintained in place by means of obstructions on the said sounding members in cooperation with the side walls of the supporting framework.

Another object of the invention is the provision of such a musical instrument in which the musical sounding members are so supported on the instrument framework as to avoid the use of metallic pins or nails thus eliminating the danger of the sounding members of contacting the said pins or nails and the consequent discordant note caused by such contact.

A further object of the invention is the provision of such sounding member mounting means which are equally adaptable for flat, circular or semi-circular sounding members whether metallic or otherwise.

A still further object of the invention is the provision of such xylophone sound member mounting means which will greatly reduce the cost of assembling the instrument.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described and illustrated in the accompanying drawing, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawing, in which

Figure 1 is a top plan view of one form of xylophone embodying my invention;

Figure 2 is a fragmental side view thereof;

Figure 3 is a cross-sectional view taken on line 3—3 Figure 1;

Figure 4 is a fragmental cross-sectional view of a somewhat modified form of my invention;

Figure 5 is a perspective view partly broken away of the sounding member used in the Figure 4 form of the invention;

Figure 6 is a view similar to Figure 4 of a still further modified form of the invention and

Figure 7 is a perspective view partly broken away of a non-metallic sounding member adapted for use in the Figure 6 form of the invention.

At the present time there are two general types of xylophones, namely those in which the musical bars are suspended from or by means of cords and secondly those in which the musical bars are held in place by means of pins or nails. In the first case the stringing of the musical bars is a comparatively long tedious and expensive operation. In the second case, the bars often come in contact with the pins when struck causing the said bars to emit distorted and discordant notes. It is to obviate these undesirable features that I have perfected my present invention.

Referring now to Figures 1 to 3 of the drawing 10 indicates the frame of my improved xylophone, the said frame comprises an end wall 11 at one end and a somewhat narrower wall 12 at the opposite end, the said end walls being connected by lower rails or side walls 13 and upper rails or side walls 14.

The upper rails 14 are each provided with semi-circular cutouts 15 through which pass musical bars or sounding members 16. The bars 16 rest upon felt or other insulating strips 17 interposed between the upper and lower rails or wall sections. In order to prevent displacement of the musical bars 16, they are each provided with lugs 18. These lugs which are struck up from the body of the bars are in close proximity to the upper side walls and act as obstructions against undue lateral movement and displacement of the bars.

While I have shown the bars 16 as being semi-circular in cross section, I desire it understood that they may just as readily be flat or circular or of any other suitable shape and may be made of any resonant material adapted for this purpose.

In Figs. 4 and 5, I have shown a modified form of the invention wherein the musical bars 16a are provided with depending lips, projections or extensions 19 whose functions are the same as those of the lugs 18 in the form of my

invention described above, however the distance between the bottom edge 20 of the lips 19 and the bottom edges 21 of any bar 16a is greater than the distance between the top of the said bar and the top 22 of the cutouts 15 thus insuring against displacement of the bars 16a from their normal position.

In Figure 6 I have shown the musical members 16b as provided with cuts or kerfs 23 the depth of which are greater than the clearances between the tops of the cutouts 15a and the tops of the said musical members 16b, thus providing against displacement of the said members.

In Figure 7 I have shown a solid semicircular musical member 16c having kerfs or slots 23a, the said member may be substituted for the member 16b in as much as with the exception of it being solid instead of semi-tubular it is in all other respects the same as the member 16b.

From the foregoing it will be seen that I have provided a xylophone or the like comprising a supporting frame having a pair of longitudinal side walls, each side wall being formed of a pair of super-imposed strips, the upper strips being formed with recesses extending upwardly from their lower edges so as to provide opposed apertures in the two side walls, a plurality of musical bars extending between the side walls and projecting through opposed apertures and a pair of spaced apart lugs on each bar extending laterally therefrom in close proximity to the respective side walls, said lugs forming means for engaging side faces of the said side walls and maintaining the bars in place on the frame.

Having described my invention what I claim as new and desire to secure by Letters Patent is:

1. For use in a frame having apertured side walls, a musical bar adapted to extend through opposite apertures in the side walls, and obstructions on the said musical bar extending laterally thereof beyond margins of the perforations in the side walls in position to engage confronting faces of the said side walls to prevent displacement of the musical bars transversely of the frame.

2. For use in a frame having apertured side walls, a musical bar adapted to extend through opposite apertures in the side walls, and ob-

structions formed integral with the said musical bar and extending laterally of the musical bar in position to engage the confronting side faces of the said side walls and prevent longitudinal displacement of the musical bar transversely of the frame.

3. A xylophone or the like comprising a supporting frame having a pair of longitudinal side walls, each side wall being formed of a pair of super-imposed strips, the upper strips being formed with recesses extending upwardly from their lower edges so as to provide opposed apertures in the two side walls, a plurality of musical bars extending between the side walls and projecting through opposed apertures and a pair of spaced apart lugs on each bar extending laterally therefrom in close proximity to the respective side walls, said lugs forming means for engaging side faces of the said side walls and maintaining the bars in place on the frame.

4. A xylophone or the like comprising a supporting frame having a pair of longitudinal side walls, each side wall being formed of a pair of super-imposed strips, having a strip of sound insulating material interposed therebetween and clamped by the strips, and the upper strip being formed with recesses extending upwardly from the lower edge so as to provide opposed apertures in the two side walls, the said recesses having arcuate walls, a plurality of semi-tubular musical bars extending between the side walls and projecting through the apertures, the said bars having their convex sides facing upwardly so that the side edges thereof rest upon the strips of sound insulating material and tongues cut longitudinally from end portions of each bar and bent to extend radially upwards from the bar in close proximity to the respective side wall, said tongues forming abutments for engaging side faces of the side walls above the apertures and maintaining the bars in place on the frame.

HARRY ZIMMERMAN.
